COMBINED BOTTLE CLOSURE AND LIQUID
WITHDRAWAL DEVICEAlbert S. Moffat, Watertown, Mass., assignor to
United Water Cooler Service, Inc., Cambridge,
Mass., a corporation

Application April 27, 1937, Serial No. 139,172

9 Claims. (Cl. 215—74)

This invention relates to a combined bottle closure and liquid withdrawal device.

One object of my invention is to provide a device having a stopper member which may be readily inserted into the neck of a bottle or other container and then expanded until it is tightly compressed against the interior surface of the neck or delivery opening of the bottle, and afterwards contracted to normal condition and removed therefrom, making such use of it repeatedly. Another object is to combine with said stopper portion a faucet so connected that liquid may be readily withdrawn at will from said container while said stopper portion is in said expanded position therein.

A further object is to so construct said device that it is simple to assemble and use, and is relatively inexpensive to produce.

The increasing use by the consumer of spring water and other beverages, which are usually delivered in large bottles, has made especially urgent the long felt need for such a combined device that is practical from a manufacturing standpoint and acceptable to the consumer because of its general simplicity and ease of operation, and it has been my main object to create a device that achieves these ends.

The foregoing and other objects which will appear as the nature of the invention is better understood, may be accomplished by a construction, combination and operative arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

In the drawing:

Figure 1 is a side elevational view of my device connected to a container or bottle, the latter being shown broken away.

Figure 2 is an enlarged sectional view of my device connected to a container, the latter being shown broken away.

Figure 3 is a sectional view taken on the line 3—3 of Figure 1.

Figure 4 is a sectional view taken on the line 4—4 of Figure 1.

As illustrated, part of my device, when in normal condition, may readily be inserted in the neck of a bottle B, and is held thereby by means of an expansible, hollow, ring-like, stopper member 15, which is preferably made of a rubber composition or other yieldable material. Said stopper

member 15 has an outer flange or shoulder 15a which is outside said bottle B and bears against the outside end of the said bottle neck as shown in Figures 1 and 2 of the drawing, being too large to enter said bottle neck. Fitted into and extending part way into said stopper member 15 is a hollow, cylindrical, metal member or bushing 16 which has a solid end portion 18 through which a central opening 17 is made, the portion of said end portion surrounding said opening 17 being screw threaded. Said end portion 18 also has a plurality of outlet openings 18a therethrough to permit the escape of the liquid from the bottle B. Said end portion 18 has a projecting portion 19 outside of said stopper member 15 which forms a shoulder that bears against the inner end of said stopper member 15.

My device has a body or outer member 22, preferably made of metal, which extends partly into the outer end of said stopper member 15; but is definitely spaced from said inner member or bushing 16, as illustrated in Figure 2 of the drawing, so that one may be moved towards the other when it is desired to tightly secure my device in said bottle B. Said body member 22 has a shoulder 23 which bears against the outer end of said stopper member 15, and has a main opening 24 communicating with which is a faucet 26, of any well known construction, which is connected to said body portion, preferably at the side thereof as shown in Figure 2 of the drawing. Said faucet 26 has the usual handle 27 to open or close it, and it is through this faucet 26 that the liquid in the bottle is withdrawn.

A rod or hollow tube 30 extends from one end of my device to the other, having a knob or handle 31 at the outside end spaced from said body member 22. Said tube is long enough to extend almost to the extremity or closed end of said bottle B, reaching beyond the maximum water line of said bottle as illustrated in Figure 1 of the drawing, so that the liquid will not escape through it, and has an opening 33 which extends through said handle 31 and its entire length to permit air to enter said bottle as the liquid is withdrawn, thereby insuring a steady flow of said liquid through said faucet 26 when it is open. Said tube 30 has a threaded portion 32 which screw threadedly connects with said threads in said bushing 16 opposite said opening 17, whereby the turning of said tube handle 31 in one direction screws the shoulder 19 of said bushing 16 tightly against said stopper member 15 causing it to yield and expand against the interior surface of said bottle neck to thereby prevent the passage

of any liquid between said bottle neck and stopper member, and firmly locking my device in position in said bottle neck as shown. Turning of said handle 31 in the other direction moves said bushing 16 in the opposite direction and said stopper member 15 returns to normal condition as the pressure on it is released, whereupon my device can be readily removed from the bottle and placed in another bottle or used again when the same bottle is refilled.

To make said body member 22 tight around said tube 30 I use a screw threaded gland nut 35 which bears against a washer 36. Said tube 30 extends through said gland nut 35 and said washer 36; but need not be screw threadedly connected thereto.

It will thus be seen that by merely turning said tube by said handle 31 my device is locked in position in said container B, and, likewise, by merely turning it in the opposite direction it may be just as readily unlocked or released from said locked position. Also by the mere turning of the faucet handle 27 the liquid may be withdrawn from said container B, as the openings for the passage of said liquid in my device are always maintained in communication with each other up to the point where the position of the faucet handle 27 controls.

My device can, of course, serve solely as a stopper, as when no withdrawal device is desired, in which event the opening in said body member for the faucet may be plugged up.

What I claim is:

1. A device of the class described comprising a hollow expansible stopper member, a bushing in contact with said stopper member having a screw threaded opening therein, a hollow body member in contact with said stopper member having an opening therein, a rod member extending from said body member into said bushing opening and having a screw threaded portion in engagement with said bushing screw thread whereby the turning of said rod members in one direction moves said bushing and presses it against said stopper member to thereby cause said stopper member to expand, said body member having an opening therein at the side thereof intermediate its ends in communication with its said hollow portion, said opening being adapted to receive a faucet.

2. A device of the class described comprising an expansible stopper member having an opening therein, a bushing in contact with said stopper member embodying a solid portion having a screw threaded opening therein and an opening for the passage of liquid therethrough, a body member in contact with said stopper member having an opening therein, said three openings being in communication with each other, a rod member extending from said body member into said bushing screw threaded opening and having a screw threaded portion in engagement with said bushing screw thread whereby the turning of said rod member in one direction moves said bushing and presses it against said stopper member to thereby cause said stopper member to expand, said body member having another opening therein in communication with and at substantially a right angle to said first-mentioned body opening adapted to receive a faucet.

3. A device of the class described comprising an expansible stopper member having an opening therein, a bushing in contact with said stopper member embodying a solid portion having a screw threaded opening therein and an opening for the passage of liquid therethrough, a body

member in contact with said stopper member having an opening therein, said three openings being in communication with each other, a tube extending from said body member into and beyond said bushing screw threaded opening and having a screw threaded portion in engagement with said bushing screw thread whereby the turning of said tube in one direction moves said bushing and presses it against said stopper member to thereby cause said stopper member to expand, said tube having an opening therein extending its entire length, said body member having another opening therein in communication with and at substantially a right angle to said first-mentioned body opening adapted to receive a faucet.

4. A device of the class described comprising an expansible stopper member having an opening therein and an outer flange at one end, a bushing part of which extends into the interior of said stopper member and part of said interior which is outside of and bears against one end of said stopper member, said bushing embodying a solid, transverse portion having an opening therein, a body member bearing against the opposite end of said stopper member adjacent said flange having an opening therein, a rod member extending from said body member opening through said stopper member into said bushing opening, said bushing and rod member having means cooperatively connected whereby movement of said rod moves said bushing and thereby presses said bushing against said stopper member to thereby cause said stopper member to expand.

5. A device of the class described comprising a hollow expansible stopper member, a bushing extending into said expansible stopper member embodying an end portion having a shoulder portion outside of said stopper member and having openings therein, and a screw threaded portion surrounding one of said openings, a hollow body portion, embodying a shoulder portion outside of said stopper member, said stopper member being so positioned that its ends may bear on said two shoulder portions, a tube extending through said body portion, stopper member and bushing, and having a screw threaded portion adapted to screw threadedly connect with said bushing screw threaded portion whereby the turning of said tube in one direction moves said bushing and presses it against said stopper member to thereby cause said stopper member to expand.

6. A device of the class described comprising a hollow expansible stopper member embodying a shoulder portion at one end, a hollow bushing, a portion of which fits into the interior of said stopper member, embodying a solid end portion having a screw threaded opening therein and a plurality of other openings, said bushing end portion embodying a shoulder portion bearing against one end of said stopper member, a body member having an opening therein, a portion of said body member extending into the interior of said stopper member, said body member embodying a shoulder portion against which the opposite end of said stopper member bears, a tube having an opening extending its entire length and embodying a screw threaded portion in engagement with said bushing screw threaded opening, said hollow tube extending from outside of and through the opening in said body portion, through said stopper member and into said bushing, said tube having a handle normally spaced from the outside end of said body portion, whereby said tube is turned to thereby press said bush-

ing shoulder portion against said stopper member to cause it to expand.

7. A device of the class described comprising a hollow expansible stopper member embodying a shoulder portion at one end, a hollow bushing a portion of which fits part way into the interior of said stopper member embodying a solid end portion having a screw threaded opening therein at the center thereof and a plurality of other 10 openings, said bushing end portion embodying a shoulder portion outside of and bearing against one end of said stopper member, a body member having an opening therein extending therethrough, a portion of said body member extending 15 into the interior of said stopper member, said body member embodying a shoulder portion against which the opposite end of said stopper member bears, a tube having an opening extending its entire length and embodying a screw 20 threaded portion in engagement with said bushing screw threaded opening, said hollow tube extending from outside of and through the opening in said body portion through said stopper member and said bushing, said tube having a handle normally spaced from the outside end of 25 said body portion, whereby said tube is turned to thereby press said bushing shoulder portion against said stopper member to cause it to expand, said body member having another opening 30 extending from the outside at substantially right angles to and in communication with its first-mentioned opening and adapted to receive a faucet.

8. A device of the class described in combination with a container having a hollow neck, said device comprising a stopper member having an opening therein and extending into and adjacent the interior surface of said neck and having an outer flange outside of and bearing against the outside end surface of said neck, a bushing a portion of which extends into the interior surface of said stopper member embodying an end portion which extends outside said stopper member into the interior of said neck and bears against one end of said stopper member, said end portion having a threaded opening therein, a body member bearing against the opposite end

of said stopper member and extending beyond the neck of said bottle and having an opening therein, a rod extending through said body member opening and said stopper member opening and into said bushing end portion opening embodying a screw-threaded portion in engagement with said bushing threaded opening whereby the turning of said rod moves said bushing and thereby presses said bushing against said stopper member to thereby cause said stopper member to 10 expand against the said interior surface of said neck portion. 5

9. A device of the class described in combination with a container having a hollow neck, said device comprising a stopper member having an opening therein extending into and adjacent the interior surface of a portion of said neck and having an outer flange outside of and bearing against the outside end surface of said neck, a bushing a portion of which extends into the interior surface of said stopper member embodying an end portion which extends outside said stopper member into the interior of said neck and bears against one end of said stopper member, said end portion having a threaded opening therein and other openings, a body member bearing against the opposite end of said stopper member outside of said bottle neck, a portion of which extends into the interior of said stopper member and a portion extending beyond the 20 neck of said bottle and having an opening therein, a tube extending through said body member opening, said stopper member opening and into said bushing end portion opening embodying a screw-threaded portion in engagement with said 25 bushing threaded opening whereby the turning of said tube moves said bushing and thereby presses said bushing against said stopper member to thereby cause said stopper member to expand against the said interior surface of said 30 neck portion, said tube having an opening therein extending its entire length, said tube extending beyond said container neck into the body of said container to a point adjacent to and spaced from, the end of said container. 35 40 45

CERTIFICATE OF CORRECTION.

March 1^h, 1939.

Patent No. 2,150,862.

ALBERT S. MOFFAT.

It is hereby certified that error appears in the printed specification of the above numbered patent requiring correction as follows: Page 2, second column, line 21, claim 1, strike out the words "said interior" and insert the same before "and" in line 22, same claim; and that the said Letters Patent should be read with this correction therein that the same may conform to the record of the case in the Patent Office.

Signed and sealed this 2nd day of May, A. D. 1939.

Henry Van Arsdale

Acting Commissioner of Patents.
